CLAIM

The ornamental design for a control panel for elevator, as shown and described.

DESCRIPTION

FIG. 1 is a front, top and right side perspective view of a first embodiment of a control panel for elevator;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is an enlarged cross-sectional view thereof; taken along line 7-7 of FIG. 2, with the internal system omitted;
FIG. 8 is a front elevational view thereof; showing section 8-8 of FIG. 2 at an enlarged scale;
FIG. 9 is a perspective view showing the control panel for elevator in an environment of use;
FIG. 10 is a front elevational view of a second embodiment of a control panel for elevator, the design being otherwise identical to the first embodiment;
FIG. 11 is a front elevational view of a third embodiment of a control panel for elevator, the design being otherwise identical to the first embodiment;

FIG. 12 is a front, top and right side perspective view of a control panel for elevator, showing a fourth embodiment thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is an enlarged cross-sectional view thereof; taken along line 18-18 of FIG. 13, with the internal system omitted;
FIG. 19 is a front elevational view thereof; showing section 19-19 of FIG. 13 at an enlarged scale;

FIG. 20 is a perspective view showing the control panel for elevator in an environment of use;

FIG. 21 is a front elevational view of a fifth embodiment of a control panel for elevator, the design being otherwise identical to the fourth embodiment; and;

FIG. 22 is a front elevational of a sixth embodiment of a control panel for elevator, the design being otherwise identical to the fourth embodiment.

The broken lines depict environmental subject matter only and form no part of the claimed design.
